[57] CLAIM

The ornamental design for the vehicle visor, as shown and described.

DESCRIPTION

- FIG. 1 is a perspective view of a first embodiment of the vehicle visor showing our new design;
FIG. 2 is a top plan view of the vehicle visor of FIG. 1;
FIG. 3 is a front elevational view of the vehicle visor of FIG. 1;
FIG. 4 is a bottom plan view of the vehicle visor of FIG. 1;
FIG. 5 is a rear elevational view of the vehicle visor of FIG. 1;
FIG. 6 is a side elevational view of the vehicle visor of FIG. 1 to a slightly enlarged scale, the opposite side being the mirror image thereof;
FIG. 7 is an enlarged cross-sectional view taken along plane VII—VII of FIG. 1;
FIG. 8 is an enlarged cross-sectional view taken along plane VIII—VIII of FIG. 1;
FIG. 9 is a perspective view of a second embodiment of the vehicle visor showing our new design;
FIG. 10 is a top plan view of the vehicle visor of FIG. 9;
FIG. 11 is a bottom plan view of the vehicle visor of FIG. 9;
FIG. 12 is an enlarged cross-sectional view taken along plane XII—XII of FIG. 9; and
FIG. 13 is a side elevation view of a third embodiment of the vehicle visor showing our new design, which differs from the second embodiment only by the addi-

tion of a contour line at the lower front corner thereof, the opposite side being a mirror image of that shown; FIG. 14 is a perspective view of the vehicle visor of FIG. 13 on a reduced scale; and FIG. 15 is a top plan view of the vehicle visor of FIG. 13 on a reduced scale it being understood that the bot-

tom is substantially the same as that of the second embodiment shown in FIG. 11.

The broken line showing of a vehicle windshield in FIGS. 1, 9 and 14 of the drawing is for illustrative purposes only and forms no part of the claimed design.
